22° Inventor
John Rodenberger.
By Walter Allen. Attorney.

Inventor

UNITED STATES PATENT OFFICE.

JOHN RODENBERGER, OF FRIENDSHIP, KANSAS.

GRAIN-DRILL.

SPECIFICATION forming part of Letters Patent No. 627,830, dated June 27, 1899.

Application filed January 16, 1899. Serial No. 702,384. (No model.)

To all whom it may concern:-

Be it known that I, JOHN RODENBERGER, a citizen of the United States of America, and a resident of Friendship, in the county of 5 Cherokee and State of Kansas, have invented certain new and useful Improvements in Grain-Drills, of which the following is a specification.

The objects of my invention are, first, to facilitate the handling and the movements of the drill, so as to secure a steady forward movement of the seeding-axle, and thus relieving the team of all burdensome weight upon the neck, and, secondly, to provide 15 means whereby all the grain can be planted at the same depth on the same line or level at any desired depth.

My invention consists in novel features of construction hereinafter described and 20 claimed, whereby I carry out the object of my invention.

In order that my invention may be fully understood, I will proceed to describe it with reference to the accompanying drawings, in 25 which—

Figure I is a perspective view of my improved grain-drill provided with one of my seeding devices. Fig. II is a side elevation of the seeding device. Fig. III is a central 30 longitudinal section of the seeding device, the colter being shown part in elevation and part in section. Fig. IV is a rear end elevation of the seeding device.

1 is the main frame, which is mounted on 35 an axle 2, which in turn is supported on a pair of ground-wheels 3. Extending from the main frame is a draft-frame constructed with an outer part 4, converging toward the front end of the machine, with a middle part 40 4^a, branching outward and downward toward the rear end of the machine, and with an inner part consisting of two longitudinal bars 4^b, secured by fastenings 5 to the side bars 5' of the main frame. The outer part of the 45 draft-frame is supported on a pilot or truck comprising an arched axle 6, whose spindles 6^a are journaled in a pair of truck or pilot wheels 7.

8 is a tongue having upper and lower tongue- 50 plates 9, which are secured by bolts 10 at the inner end, where it is supported on the truck or pilot. The arched axle, the tongue-plates,

and the outer part of the draft-frame are coupled together by a center or king bolt 11. The tongue is also braced and supported from 55 the spindles 6^a of the arched axle by means of stay-rods 12, which are looped at their lower ends around the spindles and at their upper ends are also looped around a transverse bolt 13, extending through or across the 60 tongue. The longitudinal bars 4^b are connected together in front of the main frame by means of a brace-bar 14.

15 is a rock-shaft having a hand-lever 16 and fulcrumed in clips 17, secured to the longitudinal bars 4^b between the main frame and the brace-bar 14. To this rock-shaft are secured a pair of radial eye-plates 18 for supporting the pin 19, to which the front end of the runner or cutter of my seeding device is 70 coupled.

I merely show one of my seeding devices for clearness of illustration, though there may be two or more arranged in gang form, as usual. Each of my seeding devices is constructed with a runner or cutter formed with a body 20 of trough or V shape in cross-section, so as to form a similar-shaped seed-furrow in the surface of the ground over which it is trailed. The runner is also formed with 80 a breast part 20^a for opening the seed-furrow, with an upwardly-curved neck 20^b, and with a head 20^c, having hooks 20^d engaging the pin 19 of the eye-plates 18, whereby the runner is loosely coupled to the rock-shaft 15, so 85 as to ride on the surface of the ground. The body of the runner is provided with a longitudinal opening 20^e, through which a rolling or rotary colter 21 and adjustable seed-shoe 22 project and operate. The colter has a 90 shaft 21^a, whereby it is journaled in short forward standards 23, secured within the body 20 just in rear of the breast part 20^a, so that the colter projects through the longitudinal opening 20^e and below the body. Located in 95 rear of the colter within the body are two pairs of rear standards 24, each having a vertical series of holes 24^a and secured by fastenings 25 to opposite sides of the longitudinal opening of the body. Between and to 100 these standards 24 my seed-shoe is adjustably secured. This seed-shoe is composed of a pair of plates 26, bulged at their middle parts, secured together at their ends by fastenings

27, and provided with holes 26^a at their upper edges, near their ends, which are adapted to register with the vertical series of holes 24^a in the rear standards 24, so as to adapt the 5 seed-shoe to be adjusted at both ends between the rear standards to requisite height and to be secured by transverse bolts or pins 28, whereby the seed-shoe is supported. Between the rear parts of the curved plates is 10 a spacing-piece 22^a, over which is an opening 22^b, through which the seed issues at the heel of the seed-shoe.

29 is a seed-tube pivoted at its lower end by a cross-rod 30 to the seed-shoe, so as to 15 deliver the seed to the latter for distribution. The front end 26^b of the seed-shoe is sharpened, so as to follow in the cut made by the rotating colter.

31 is a seedbox connected by a rubber seed-20 fluke 32 with the seed-tube 29. For the purpose of holding down the rear end of the runner or cutter to its work or for elevating it in going to or from the field I provide the following means: 33 is a spring connected at its 25 lower end to the rear end of the runner and at its upper end to the short arm 34^a of a hand-lever 34, mounted on a rod 35, supported on the rear end of the main frame.

The truck or pilot located under the front 30 end of the draft-frame permits each wheel to play underneath the front end of the draft-frame, thus enabling the team to swing a quarter-circle perfectly independent, when a forward movement of the team turns the machine.

35 By the combination of the V-shaped runner or cutter colter and the peculiar construction and mounting of the seed-shoe I am enabled to form a furrow in the surface of the ground 40 in advance of the colter, which is set deeper than the seed-shoe, so as to clear the way for the seed-shoe by severing all weeds and trash in advance thereof and preventing choking and clogging of the seed-shoe, which is sharpened on its forward end and adjustable in 45 depth. The seed issues from the seed-shoe over the spacing-piece at the bottom through the opening at the rear end of the seed-shoe.

The V-shaped runner or cutter acts or 50 serves as a perfect gage in passing over uneven surfaces and high loose earth, and the seed is thus deposited or trailed into the furrow at any desired depth below the bottom of the runner.

55 Having thus described my invention, the following is what I claim as new therein and desire to secure by Letters Patent:

1. A grain-drill comprising a main frame, a main axle, ground-wheels, a draft-frame 60 constructed with an outer part converging toward the front end of the machine, with a middle part branching outward and downward toward the rear end of the machine, and with an inner part consisting of two longitudinal bars secured to the main frame, the truck 65 consisting of an arched axle having spindles, and a pair of truck-wheels, in which the spin-

dles are journaled, a tongue having upper and lower tongue-plates, the center bolt whereby the said tongue-plates, the said arched axle 70 and the said outer part of the draft-frame are coupled together, and the stay-rods whereby the tongue is supported from the spindles of the arched axle; substantially as described.

2. A grain-drill comprising a main frame, 75 a main axle, ground-wheels, a draft-frame constructed with an outer part converging toward the front end of the machine, with a middle part branching outward and downward toward the rear end of the machine, and with an inner part consisting of two longitudinal bars secured to the main frame, the brace-bar whereby the longitudinal bars are connected together in front of the main frame, the truck consisting of an arched axle having 85 spindles, and a pair of truck-wheels in which the spindles are journaled, a tongue having upper and lower tongue-plates, the center bolt whereby the said tongue, the said axle, and the said outer part of the draft-frame are 90 coupled together, and the stay-rods whereby the tongue is supported from the spindles of the arched axle; substantially as described.

3. A grain-drill comprising a main frame, a main axle, ground-wheels, a draft-frame, a 95 truck, a tongue, a rock-shaft, having a hand-lever, a runner, coupled to the rock-shaft, and adapted to trail on the ground and to open a furrow, a colter and seed-shoe mounted within the runner and working through and in connection with the runner, and means for conducting the seed to the seed-shoe; substantially as described.

4. A grain-drill comprising a main frame, a main axle, ground-wheels, a draft-frame, a 105 truck, a tongue, a rock-shaft, having a hand-lever, a runner constructed with a V-shaped body having a longitudinal opening, with a breast part, with a neck, and with a head, coupled to the rock-shaft, and adapted to trail 110 on the ground and to open a furrow, a colter, and seed-shoe mounted within the runner and working through and in connection with the runner, and means for conducting the seed to the seed-shoe; substantially as 115 described.

5. A seeding device comprising a runner adapted to trail on the ground and to open a furrow, a colter mounted within and working through the runner to sever the weeds 120 and trash beneath the runner, and a seed-shoe mounted within the runner and working through and in connection with the runner, and located in rear of the colter; substantially as described.

6. A seeding device comprising a runner adapted to trail on the ground and to open a furrow, constructed with a V-shaped body having a longitudinal opening, with a breast part, with a neck, and with a head, coupled 125 to the rock-shaft, and adapted to trail on the ground and to open a furrow, a colter, and a seed-shoe mounted within the runner and working through and in connection with the

runner, and means for conducting the seed to the seed-shoe; substantially as described.

7. A seeding device comprising a runner having a longitudinal opening and adapted to trail on the ground and to open a furrow, a pair of short forward standards located within the runner adjacent to the breast portion, a rotary colter journaled in the forward standards and working through a longitudinal opening, the two pairs of rear standards each having a vertical series of holes and located within the runner on opposite sides of the longitudinal opening, an adjustable seed-shoe composed of a pair of plates

curved outward at their middle parts, secured together at their ends and provided with holes at their upper edges near their ends, adapted to register with the vertical series of holes in the rear standards, transverse bolts whereby the seed-shoes are adjusted on the rear standards, the spacing-piece at the bottom of the seed-shoe, and the seed-opening at the heel of the seed-shoe; substantially as described. 15 20
